UNITED STATES PATENT OFFICE

HARTT H. EASON, OF CHICAGO, ILLINOIS.

DESIGN FOR A LAMP.

No. 39,374.

Specification for Design.

Patented June 23, 1908.

Application filed April 16, 1908. Serial No. 427,540. Term of patent 7 years.

To all whom it may concern:

Be it known that I, HARTT H. EASON, a citizen of the United States, residing at Chicago, in the county of Cook and State of Illinois, have invented a new, original, and ornamental Design for Lamps, of which the following is a specification, reference being had to the accompanying drawing, forming a part thereof.

The figure is a view in side elevation of a lamp, showing my new design.

I claim:

The ornamental design for a lamp as shown.

HARTT H. EASON.

In the presence of—

NELLIE E. GEORGE,
HARRY L. CROMER.
